US00D592136S

(12) **United States Design Patent**
Chu et al.

(10) **Patent No.:** US D592,136 S
(45) **Date of Patent:** ** May 12, 2009

(54) **BATTERY CONNECTOR**

(75) Inventors: **Ping-Chuan Chu**, Hsin-Tien (TW); **Hui Wang**, Hsin-Tien (TW)

(73) Assignee: **Advanced Connectek Inc.**, Hsin-Tien, Taipei Hsien (TW)

(**) Term: **14 Years**

(21) Appl. No.: **29/321,879**

(22) Filed: **Jul. 25, 2008**

(30) **Foreign Application Priority Data**

Jan. 25, 2008 (TW) 97300422

(51) **LOC (9) Cl.** 13-02

(52) **U.S. Cl.** D13/120

(58) **Field of Classification Search** D13/102-106, D13/110, 118-121, 133, 146-149, 154, 184; 429/96-100, 163, 176; 439/83, 108, 166, 439/500, 577, 630, 660, 680, 700, 773.1, 439/862

See application file for complete search history.

(57) **CLAIM**

The ornamental design for a battery connector, as shown.

DESCRIPTION

FIG. 1 is a perspective view of a battery connector showing our new design;

FIG. 2 is a front view thereof;

FIG. 3 is a rear view thereof;

FIG. 4 is a left side view thereof;

FIG. 5 is a right side view thereof;

FIG. 6 is top view thereof;

FIG. 7 is a bottom view thereof; and,

FIG. 8 is another perspective view thereof.

The broken lines shown in the drawings are included for the purpose of illustrating environmental structure and form no part of the claimed design.

1 Claim, 8 Drawing Sheets

FIG.1

FIG.2

FIG.3

FIG.4

FIG.5

FIG.6

FIG.7
